(57) **ABSTRACT**

A new apple tree named 'Isadora' apple tree, distinguished by its suitability for growing regions with low chilling hours; immunity to *Glomerella* leaf spot (*Colletotrichum* spp.); and relatively late harvest window as compared to varieties grown in the same low-chill regions. 'Isadora' is further notable for its fruit, which has very good flavor and sweetness and is firm and very crunchy. The fruit of 'Isadora' does well in long-term storage.

8 Drawing Sheets

1

Latin name: *Malus domestica* Borkh.
Variety denomination: 'Isadora'.

BACKGROUND OF THE VARIETY:

'Isadora' is a new and distinct variety of apple tree (*Malus domestica* Borkh) obtained from a controlled cross of 'Cripps Pink' (female parent, U.S. Plant Pat. No. 7,880) x 'Imperatriz' (male parent, not patented) carried out at Caçador, Santa Catarina, Brazil in 2001. Seeds obtained from the cross were planted at Caçador, and 'Isadora' was selected from the resulting seedlings for propagation and further observation under breeder's reference 'M 10/09'. 'Isadora' was first asexually propagated by bench grafting onto M.9 rootstock (not patented) at Caçador in 2004, and has since been observed to remain true to type through successive asexually propagated generations.

2

Comparisons of 'Isadora' to its parents and to similar variety 'Alpigala' (U.S. Plant Pat. No. 30,061) are shown in Tables 1, 2 and 3 below.

TABLE 1

Comparison of 'Isadora' to Female Parent 'Cripps Pink'		
Characteristic	'Isadora'	'Cripps Pink'
Pattern of overcolor	Weakly defined flush with Solid flush strongly defined stripes	
Amount of overcolor	About 80%	50% to 60%
Juiciness	More juicy than 'Cripps Pink'	Less juicy than 'Isadora'
Russetting of skin	Very little on cheeks; moderate around stalk cavity	None
Harvest timing	One week earlier than 'Cripps Pink'	One week later than 'Isadora'

TABLE 2

Comparison of 'Isadora' to Male Parent 'Imperatriz'		
Characteristic	'Isadora'	'Imperatriz'
Fruit size	Smaller than 'Imperatriz'	Larger than 'Isadora'
Fruit skin	Thicker	Thinner
Tree vigor	Moderate	Vigorous

BRIEF DESCRIPTION OF THE VARIETY

The 'Isadora' apple tree is distinguished by its suitability for growing regions with low chilling hours; immunity to *Glomerella* leaf spot (*Colletotrichum* spp.); and relatively late harvest window as compared to 'Gala' and 'Fuji' varieties grown in the same low-chill regions. 'Isadora' is further notable for its fruit, which has very good flavor and sweetness and is firm and very crunchy. The fruit of 'Isadora' does well in long-term storage.

TABLE 2-continued

Comparison of 'Isadora' to Male Parent 'Imperatriz'		
Characteristic	'Isadora'	'Imperatriz'
Tree habit	Spreading	Upright
Fruit storageability	6 months	3 months

TABLE 3

Comparison of 'Isadora' to Similar Variety 'Alpigala'		
Characteristic	'Isadora'	'Alpigala'
Fruit overcolor	Red 45A	Purple N77A
Firmness of fruit flesh	10.6 kg/cm ²	7.1 kg/cm ²
Harvest timing	Later (October)	Earlier (early September)
Tree bark color	Grey-brown 199C	Brown 200C
Date of full bloom (2018)	Apr. 19	Apr. 23

BRIEF DESCRIPTION OF THE PHOTOGRAPHS

The accompanying photographs were taken at Seiches sur le Loir, France of trees planted in 2016. Flower photos were taken in 2018, fruit photos in 2019, and leaves and additional fruit photos in 2020.

FIG. 1 is a photograph of an 'Isadora' apple tree with leaves and fruit;

FIG. 2 is a photograph of a bare 'Isadora' apple tree;

FIG. 3 is a photograph of a flower of an 'Isadora' apple tree;

FIG. 4 is a photograph of a one-year-old shoot of an 'Isadora' apple tree;

FIG. 5 is a photograph of leaves of an 'Isadora' apple tree;

FIG. 6 is a photograph of the trunk of an 'Isadora' apple tree;

FIG. 7 is a photograph of whole fruit from an 'Isadora' apple tree; and,

FIG. 8 is a photograph of sectioned fruit from an 'Isadora' apple tree.

DETAILED BOTANICAL DESCRIPTION OF THE VARIETY

The following detailed botanical description were obtained at Seiches sur le Loir, France during 2019 unless otherwise noted, of trees planted in 2016 and grown on Pajam®2 'Cepiland' (U.S. Plant Pat. No. 7,715) rootstock. All colors are described according to The R.H.S. Colour Chart (Royal Horticultural Society, 6th ed. 2019 reprint). It should be understood that the characteristics described will vary somewhat depending upon cultural practices and climatic conditions, and will vary with location and season. Quantified measurements are expressed as an average of measurements taken from a number of individual plants of the new variety. The measurements of any individual plant or any group of plants of the new variety may vary from the stated average.

Tree:

Vigor.—Medium.

Type.—Ramified.

Habit.—Spreading.

Bearing.—On shoots.

Spread of mature tree.—1.5 meters (after pruning).

Height.—2.0 m (after pruning).

Trunk diameter (at 30 cm above the graft).—48 mm.

Bark texture.—Slightly rough.

Bark color.—Grey-brown 199C tinged with yellow-orange 22A.

Lenticel length.—5 mm.

Lenticel width.—2 mm.

Lenticel height.—1 mm.

Lenticel shape.—Oblong.

Lenticel color.—Grey-brown 199C.

Lenticel density.—2 per cm².

Branch (fruiting branches located at around 1 m above the graft union):

Length.—90 cm.

Diameter.—17.8 mm.

Crotch angle.—60°.

Bark color.—Grey-brown 199C.

Lenticel length.—2 mm.

Lenticel width.—1 mm.

Lenticel height.—0.5 mm.

Lenticel shape.—Oblong.

Lenticel color.—Yellow-white 158A.

Lenticel density.—6 per cm².

One year old shoot:

Length.—28 cm.

Diameter.—5 mm.

Color.—Greyed-orange 165A.

Pubescence.—Weak.

Internode length.—4 cm.

Lenticel length.—1 mm.

Lenticel width.—1 mm.

Lenticel height.—0.5 mm.

Lenticel shape.—Round.

Lenticel color.—Yellow-white 158A.

Lenticel density.—Few.

Flower buds (at balloon stage):

Quantity per spur.—5 to 7.

Bud shape.—Conical to round.

Apex shape.—Round.

Length.—11 mm.

Diameter.—11 mm.

Color.—Red-purple 58A.

Flowers:

Diameter of fully open flower.—37 mm.

Flower depth/height.—12 mm.

Relative position of petal margin (overlapping, touching, or free).—Overlapping.

Number per cluster.—5 to 7.

Fragrance.—Strong.

Date of first bloom.—April 16th (2018, Loire Valley, France) 2 days before 'Golden Delicious' (not patented).

Date of full bloom.—April 19th (2018, Loire Valley, France) 4 days before 'Golden Delicious'.

Pollination requirement.—Pollenizer required; 'Granny Smith', 'Idared', 'Golden Gem' (none patented).

Petals:

Number per flower.—5.

Petal shape.—Elliptical.

Length.—21 mm.

Width.—14 mm.

Apex shape.—Rounded.

Base shape.—Acuminate.

Margin.—Smooth.

<i>Color of upper surface.</i> —White N155D with red-purple N74C.	5	<i>General shape in profile.</i> —Globose.
<i>Color of lower surface.</i> —White N155D with red-purple 70B.		<i>Position of maximum diameter.</i> —At equator.
Pistils:		<i>Ribbing.</i> —Moderate.
<i>Quantity.</i> —5.		<i>Crowning at calyx end.</i> —Strong.
<i>Length.</i> —12.5 mm.		<i>Bloom of skin.</i> —Absent or weak.
<i>Color.</i> —Yellow-green 145B with yellow-green 146C.		<i>Greasiness of skin.</i> —Weak.
Stigma:		<i>Background color of skin.</i> —Yellow 4A at harvest; yellow 7D after storage.
<i>Length.</i> —1 mm.	10	<i>Over color of skin.</i> —Red 47A at harvest; red 45A after storage.
<i>Color.</i> —Yellow-green 145B.		<i>Amount of over color.</i> —80%.
<i>Position relative to anthers.</i> —Same level.		<i>Intensity of over color.</i> —Medium to dark.
Style:		<i>Pattern of over color.</i> —Weakly defined flush with strongly defined stripes.
<i>Length.</i> —9.4 mm.		<i>Width of stripes.</i> —Medium.
<i>Color.</i> —Yellow-green 145B.	15	<i>Lenticel density.</i> —Medium.
Ovary:		<i>Lenticel size.</i> —Medium.
<i>Length.</i> —2.1 mm.		<i>Amount of russet around stalk cavity.</i> —Medium.
<i>Width.</i> —1.4 mm.		<i>Amount of russet on cheeks.</i> —Very small.
<i>Color.</i> —Yellow-green 146C.		<i>Area of russet around eye basin.</i> —Absent.
Anthers:		<i>Length of stalk.</i> —27 mm.
<i>Quantity.</i> —19 to 20.	20	<i>Diameter of stalk.</i> —2 mm.
<i>Length.</i> —1.5 mm.		<i>Stalk color.</i> —Greyed-orange 165A.
<i>Width.</i> —1.3 mm.		<i>Depth of stalk cavity.</i> —17 mm.
<i>Color of anther.</i> —Yellow 8C.		<i>Width of stalk cavity.</i> —36 mm.
<i>Presence of pollen.</i> —Present in moderate quantities.	25	<i>Depth of eye basin.</i> —9 mm.
<i>Color of pollen.</i> —Yellow 8C.		<i>Width of eye basin.</i> —31 mm.
Pedicel:		<i>Diameter of eye.</i> —7 mm.
<i>Length.</i> —24 mm.		<i>Length of sepal.</i> —6 mm.
<i>Diameter.</i> —1 mm.		<i>Firmness of flesh.</i> —10.6 kg/cm ² .
<i>Color.</i> —Greyed-purple 183A.	30	<i>Flesh texture.</i> —Medium, somewhat granular.
Sepals:		<i>Number of locules.</i> —5.
<i>Quantity.</i> —5.		<i>Locule length.</i> —14 mm.
<i>Color of upper surface.</i> —Yellow-green 145B.		<i>Locule width.</i> —10 mm.
<i>Color of lower surface.</i> —Yellow-green 145B.		<i>Aperture of locules.</i> —Moderately open.
<i>Length.</i> —7 mm.	35	<i>Aroma, flavor.</i> —Sweet, subtle flavor.
<i>Width.</i> —3 mm.		<i>Juiciness.</i> —Very juicy.
<i>Sepal shape.</i> —Acuminate.		<i>Brix.</i> —14.9° Brix.
<i>Apex shape.</i> —Pointed.		<i>Flesh color.</i> —Yellow 4D.
<i>Margin.</i> —Smooth, pubescent.		40 Seeds:
Leaves:		<i>Quantity per fruit.</i> —Average 9.8.
<i>Shape.</i> —Ovate		<i>Length.</i> —9 mm.
<i>Length.</i> —99 mm.		<i>Width.</i> —5 mm.
<i>Width.</i> —47 mm.		<i>Shape.</i> —Elongated oval.
<i>Blade margin.</i> —Serrate.		<i>Color.</i> —Greyed-orange N167A.
<i>Apex.</i> —Acute.	45	45 Harvest:
<i>Base shape.</i> —Wedge-shaped, asymmetric.		<i>Harvest date.</i> —October 23 (2019); between 'Fuji' and 'Cripps Pink'.
<i>Profile in cross section.</i> —Flat.		<i>Number of picks.</i> —2.
<i>Leaf color—upper surface.</i> —Green 137A, primary vein yellow-green 149D.		<i>Harvest yield.</i> —22 kg per tree (2020 harvest from trees planted in 2016).
<i>Leaf color—lower surface.</i> —Greyed-green 194A.	50	Disease resistance/susceptibility: Resistance to <i>Glomerella</i> leaf spot (<i>Colletotrichum</i> spp.).
<i>Attitude in relation to shoot.</i> —Upward.		Eating quality: Very good.
Petiole:		55 Shipping quality: Good.
<i>Length.</i> —27 mm.		Storageability: Long, up to 6 months.
<i>Diameter.</i> —2 mm.		Market use: Fresh consumption.
<i>Color.</i> —Yellow-green 149D with greyed-purple 185B near base.	55	 The invention claimed is:
Fruit:		1. A new and distinct apple tree named 'Isadora' substantially as described and illustrated herein.
<i>Quantity per cluster.</i> —5.		
<i>Diameter.</i> —74 mm.		
<i>Height.</i> —67 mm.		
<i>Ratio of height to width.</i> —0.9.		
<i>Weight.</i> —169 g.
